ASSIGNOR TO E. ROY ALLING, OF KENMORE, NEW YORK

ROTARY CAN WASHER

Application filed July 13, 1928. Serial No. 292,347.

This invention relates to article washing machines, and particularly to the type which may be advantageously employed for the washing of such articles as milk cans and covers, or other containers.

An object of the invention is to generally improve, simplify and render more efficient and economical article washing machines of this type.

Another object of the invention is to provide an improved article washing machine with which articles may be washed in a manner to provide thorough cleansing and subsequent complete sterilization thereof with a minimum of treatments, which will be compact, simple, effective and economical in operation, which will require a minimum of supervision and operating attention, and which will be relatively inexpensive.

Various other objects and advantages will be apparent from the following description of one embodiment of the invention, and the novel features will be particularly pointed out hereinafter in connection with the appended claims.

In the accompanying drawings:

Fig. 1 is a sectional elevation of a milk can washing machine constructed in accordance with this invention.

Fig. 2 is a top plan of the same, with portions broken away to illustrate details otherwise concealed thereby.

Fig. 3 is a sectional plan of the same, with the section taken approximately along the line 3—3 of Fig. 1.

Fig. 4 is a longitudinal, sectional view of one of the mixing nozzles forming a part of the washer.

In the illustrated embodiment of the invention, the washing occurs within the casing 1, which may, for convenience, be cylindrical in shape, and is provided at one side with an opening 2 through which the cans and covers or other articles may be loaded and unloaded during the continued operation of the machine.

The casing may have a platform 3 at the base of the opening 2 to facilitate the loading and unloading of the cans and covers.

Within the casing 1, a can and cover sup-

port 4 may be supported for rotation by means of a vertical shaft 5. This shaft extends upwardly through the top of the casing and carries at its outer end a Geneva transfer gear 6 through which rotation of the support 4 may be effected. The support 4 may include a small cylindrical shell 4a disposed axially about the shaft 5 and a plurality of walls or vanes 7 projecting radially and outwardly from the shell 4a to provide between them radially extending compartments in which the cans are disposed in an inverted position.

The support 4 also includes at its lower end an apertured or grid-like frame or base 8 upon which the cans rest while inverted, and brackets 9 may be provided at the inner ends of the pockets formed by the vanes or walls 7 to prevent the cans from tipping over and to aid the attendant in quickly and accurately positioning the cans for alignment with or over the jets used in the cleansing operations. The lower outer corners of the vanes or walls 7 may be notched as at 10, and the base 8 may be provided with bent wire hooks 75 or supports 11 for supporting the covers midway between each two compartments and in the notches 10 of the radial walls. The mounted position of one such cover is shown by the dash lines 12 in Fig. 1.

Any suitable source of power may be employed for operating the shaft 5, and by way of illustration such a source of power may be applied through a pulley 13 mounted on a shaft 14. This shaft extends into a housing 15 and has a worm wheel drive connection within said housing to a shaft 16 which extends towards the shaft 5 but in a direction crosswise thereof. The shaft 16 may be connected by mitre gearing 17 to a rotary driving element 18 carrying a Geneva transfer pin 19, and also having a cylindrical locking surface 20 extending peripherally of the element from said pin.

The locking pin 19 is adapted to engage in the slots 21 in the Geneva transfer wheel 6, and between the notches 21, the cylindrical locking portions 20 engage in concave notches or locking faces 22. The gear 6 and therefore the parts carried thereby will be moved

intermittently through increments of movements by rotation of the pulley 13 and during all periods between such intermittent movements, the shaft 5 and parts carried thereby 5 will be locked against angular displacement or movement.

The bottom part of the casing 1 is provided with a plurality of reservoirs or tanks 23, 24 and 25, (Fig. 3) arranged in succession in the direction of travel of the articles through the casing, so as to serve as reservoirs for collecting or holding liquids employed in the cleansing and treatment of the cans and covers. Referring particularly to Fig. 3, 10 the cans, after their first increment of movement from the loading opening 2, will be positioned over a preliminary rinse jet 26 by which the cans may be given, while inverted, a preliminary jet of liquid to rinse out such 15 contents of the can as may be easily carried out by such a treatment.

While the cans are in either of the next two successive positions, they will be disposed over jet creating devices 27 and 28 20 by means of which the cans will be subjected to hydraulic jets of a cleansing solution, such as a caustic solution. These successive treatments with the cleansing solution effectively remove all foreign matter from within the 25 cans, as usual in the art. The drainage of the cleansing solution from the cans will collect in the tank 24 for re-use as usual in the art.

When the cans are in the next successive 30 position they will be disposed above the tank 25 containing a hot water or other rinsing liquid. A jet device 29 is connected by pipe 30 to suitable mechanism (not shown, but usual in the art) for subjecting the cans to 35 a hot rinse liquid, such as water, the liquid or water draining from the cans into the tank 25.

The covers are similarly treated while above the tanks 24 and 25. The water or 40 rinsing liquid in the tank 25 is heated before it is directed against the cans and covers and serves as a suitable source of heat for the sterile rinse to which the cans are to be subsequently subjected or treated, as will be 45 presently explained.

The tank 25 also extends beneath the cans while the cans are in the next two positions. A pair of coils 31 and 32 are disposed within the tank 25 preferably, but not necessarily, 50 concentrically of one another so as to be partly or entirely immersed in the rinse liquid collecting in the tank 25. The coils 31 and 32 are approximately below the cans 55 while the cans are supported in the next successive position after treatment from the rinsing jet device 29, as will be observed from Fig. 3. One end of the outer coil 31 is connected to a water supply pipe 33 leading to 60 a valve 34. One end of the inner coil 32 is

similarly connected by a pipe 35 to another valve 36.

The valves 34 and 36 may be connected by pipes 37 and 38 (Fig. 2) to a common water supply pipe 39, leading to any suitable source 70 of clean water. The upper or other end of the larger coil 31 (Figs. 1 and 3) is connected to the lower end of a nozzle device 40. This nozzle device is shown more particularly in Fig. 4, and has a central passage 41 leading from the connection to the coil 31 to a discharge orifice or passage 42, which may be centrally of the upper end of the nozzle device. 75

The passage 42 is preferably smaller than the passage 41, so as to cause the water or liquid leaving the device to have considerable velocity. Another passage 43 is provided in the nozzle device 40, surrounding but separate from the passage 41, and this passage 80 43 also opens upwardly through the upper end of the nozzle device through a circular or frusto-conical passage 44 which is preferably concentric with the passage 42. 85

To provide this passage 44, the discharge 90 end of the casing of the device 40 may be provided with a sleeve 40a which is threaded over an open end of the body of the device. This sleeve 40a, at its projecting end has a frusto-conical inner periphery which fits 95 over a similarly frusto-conical end of a tubular stem 40b extending from the interior of the casing of the device 40 through the open end thereof into the sleeve 40a. By threading the sleeve 40a to variable extents upon the casing of the device 40, the clearance between the tapered end of the stem 40b and the inner periphery of the sleeve, which constitutes the passage 44 may be adjustably varied so as to vary the amount of steam 100 which will be discharged. The free end of the sleeve 40a may be exteriorly threaded for connection thereto of a pipe extension when desired. Thus any fluid passing through the passage 43 will leave the nozzle device passing through the circular frusto-conical passage 44 which converges towards the discharge end of the nozzle device in such a manner that the fluid leaving it will have the form of a cone-like shell converging into 105 the fluid jet leaving the passage 42. A steam supply pipe 45 is connected to the passage 43 of the nozzle device for supplying steam thereto. The pipe 45 is in turn connected to a valve 46, and the valve in turn is connected 110 to a main steam supply pipe 47, Fig. 2. 115

The upper end of the other coil 32 is connected to a nozzle device 48 similar to the nozzle device 40, the coil 32 being connected to the longitudinal central passage thereof 120 corresponding to the passage 41 of Fig. 4. A steam supply pipe 49 is connected to the nozzle device 48 through the outer passage 125 thereof corresponding to the passage 45 of Fig. 4. The pipe 49 is connected to a valve 130

50 which is also connected to the main steam supply pipe 47, Fig. 2.

5 A union member 48a is connected to the nozzle device 48 by being threaded upon the discharge end of the sleeve thereof corresponding to the sleeve 40a and member 48a is connected to a pipe 51 which extends through the casing to the exterior thereof, then along the casing to a point at which it may terminate in a nozzle device 52, Figs. 2 and 3, disposed to spray through an aperture in the casing, either or both fluids against the inside faces of the covers, as will be observed from Fig. 3. For this purpose, the covers 10 will be disposed with their under or inner faces facing outwardly, that is, directed towards the lateral wall of the casing 1.

15 The nozzle device 40 is so disposed and positioned that it directs the discharged fluids 20 upwardly into the inverted cans disposed above it and any drainage from the cans, as well as the drainage from the covers subjected to the spray from the nozzles 52, will drain into the tank 25 and form thereby a 25 continuous replenishing supply of rinse water therefor.

20 The steam supply pipe 49 communicates with a nozzle device 53 opening downwardly through the top of the casing for blowing 30 steam directly upon the bottoms of the inverted cans, which because of their inverted positions, will be uppermost. This jet of steam blows off any collection of moisture thereon.

35 At another point along the lateral wall of the casing 1, the steam pipe 49 has communication with another blow off nozzle 54 which opens through the lateral wall of casing 1 in a position to blow a jet of steam 40 against the covers to blow off excessive moisture therefrom.

45 The steam supply pipe 45 may also have a branch 55 extending beneath the revolving frame or base 8 and terminating in an upwardly directed nozzle device 56 for directing upwardly into the inverted cans a jet of steam for sterilizing purposes while the cans are in a position occupied subsequently to the positions over the coils where they were subjected 50 to the sterile rinse.

55 In the last position of the cans before they again reach the unloading opening 2, they will be disposed above an upwardly opening pipe 57 directing a current or blast of drying air upwardly into the cans to dry the same before they are removed.

60 The valves 34, 36, 46 and 50 are preferably arranged side by side in a row and are operated separately by cams 58, 59, 60 and 61 respectively. These cams are mounted on a common control shaft 62 which is rotatably supported in suitable bearings on the top of the casing, and this shaft carries a mitre gear 63e which meshes with and is driven from 65 another mitre gear 64 connected to and ro-

tating with the Geneva transfer member 18. The cams 58 to 61 inclusive will thus be operated in synchronized relation to the movements of the inverted cans in the casing 1, and the valves 34, 36, 46 and 50 will thus be operated in definitely synchronized relation to the rotation of the cans, to control the passage of steam and water to the cans in the desired treatments of the cans while within the casing 1.

70 In the operation of the device, an attendant inserts the cans and covers in the radial chambers formed by the walls or vanes 7 through openings 2. The pulley 13 is operated from any suitable motive power, and the Geneva transfer mechanism 18 will at intervals unlock the gear 6 and move it through an increment of angular movement of such an extent that the radial chamber carrying the can and cover will move through one increment of movement within the casing 1 and over the preliminary rinse jet 26, Fig. 3.

75 During continued rotation of the Geneva element 18, it will, after lapse of a suitable interval, again release the wheel 6 and move it through another increment of angular movement, which causes a further movement of the can and cover support 4 to carry the can above the cleansing solution tank 24 with the can immediately above the jet 27.

80 Between these two movements, however, the attendant has inserted another can and cover into the next radial chamber and this during the second movement has moved over to a position over the preliminary rinse jet 26.

85 It will be understood of course that the cans and covers are inserted in proper positions on the support 4 in succession as the radial chambers come opposite the loading and unloading opening 2, any washed cans and covers being removed before the cans to be washed are loaded into any compartment. During the continued intermittent movement of each can with the support 4, it will 90 be subjected to jets of suitable cleansing solutions from the jet devices 27 and 28, and then subjected to rinsing jets from the device 29.

95 During rotation of the Geneva element 18, the shaft 62 will be correspondingly rotated and thereby the valves 58 to 61 will be operated in a desired sequence in synchronized relation to the movements of the cans through the casing. When the water valves 34 and 36 are closed, the coils 31 and 32 will always be filled and will be in heat interchanging relation with the hot rinsing liquid or water in the tank 25. Thus there will always be within the coils 31 and 32 charges of water 100 which have been heated by the hot water or liquid in the tank 25.

105 Upon the opening of the valves 34 and 36, the entrance of further water into the coils 110 will force out this previously heated water 115

through the nozzle devices 40 and 48 and against the articles to be washed, such as the cans and their covers. At or about the same time, however, the steam valves 46 and 50 5 will also be opened to admit steam to the nozzle devices, and this steam will mix with and further heat the discharged hot water to a temperature sufficiently high enough to sterilize, by rinsing action, the cans and 10 their covers.

The steam valves are preferably held open shortly after the water valves are closed, so that the cans and covers will be subjected to a short interval of steaming after the cessation 15 of the sterile rinse of hot water, to further insure complete sterilization of the cans and covers.

When the cans and covers move into the next position, they will be subjected to the 20 blow off jets of steam from nozzles or blow-off devices 53 and 54, by which collected moisture thereon is blown off, and at the same time the insides of the cans will also be subjected to a sterile jet of steam from the device 56. The cans next move above the hot 25 air supply device 57 at which time they are dried before they reach the unloading opening 2.

By reason of the constant addition of a 30 sterile rinse water to the tank 25, there will be an accumulation, which overflows to a greater or lesser extent as may be desired, into the cleansing solution tank 24 to replenish the same. The rinsing liquid in the tank 35 24 has considerable heat which would be lost to some extent were it not utilized to heat preliminarily the water in the coils 31 and 32, which heated water is in turn utilized to provide the sterile rinse for the articles.

40 By using the coils 31 and 32 in this manner, the device is made compact, the use of additional heaters is avoided, and since the heating of the water for the sterile rinse requires time, this heating is partially taking place 45 continually and in advance of the need. While the temperature of the water in the coils 31 and 32 thus obtained would not usually be sufficient to insure the desired temperature for the sterilizing rinse liquid, this 50 deficiency is made up by the admission of steam to the discharged water at the time of discharge, in an exceptionally simple manner.

It will also be noted in Fig. 4 that the steam 55 passages 43 and 44 surround the passages 41 and 42 and therefore have a heat interchange relation therewith, so that there will be some heating of the liquid in the passages 41 and 42 before or while the liquid is discharged therefrom. By reason of the nature 60 of the conical jets of steam of variable volume directed or focused into the jet of discharged sterile rinse water, a very efficient and effective mixture of the steam and water 65 is obtained, and the mixture striking the ar-

ticles may be given a uniformly high but selective variable temperature.

It will be obvious that various changes in the details which have been herein described and illustrated in order to explain the nature of the invention, may be made by those skilled in the art within the principle and scope of the invention as expressed in the appended claims.

It will also be observed that various features of the invention herein set forth, are equally applicable to washers in which the articles are moved in paths which are not necessarily circular or closed.

We claim:

1. In an article washing machine, means for supporting the articles to be washed and moving them progressively in a prescribed path, means for subjecting the articles during their progress to the action of a washing liquid and then a hot water rinse while in successive positions, a coil immersed in the hot water used for the hot water rinse, means connected to one end of the coil enabling connection of that end of the coil to a supply of clean water, a steam supply pipe, and means connected to the other end of the coil and to said supply pipe for directing steam and water separately or together against the articles being washed subsequently to said hot water rinse whereby said article may be given a hot sterile rinse; and means for controlling selectively the passage of water and steam through said directing means.

2. In an article washing machine, means for supporting the articles to be washed and moving them through a prescribed path, means for subjecting the articles to the action of a hot liquid while in said path, a coil immersed in a part of said hot liquid for heat interchange therewith, a continuous pressure, clean water supply connection to one end of said coil, means connected to the other end of said coil for directing water therefrom against the articles in said path, means for mixing steam with the water leaving said coil to further heat it, and means for controlling selectively the flow of water through said coil and the addition of steam to the water leaving the coil, whereby the temperature of the water may be raised to the desired extent and the steam continued after the water flow is discontinued.

3. In an article washing machine, means for supporting the articles to be washed and moving them through a prescribed path, means for subjecting the articles to the action of a hot liquid while in said path, a coil immersed in a part of said hot liquid for heat interchange therewith, a clean water supply connection to one end of said coil, a discharge device connected to the other end of the coil for discharging water from said coil against the articles while in said path, means for discharging steam against said ar-

- ties in a manner to cause its mixture with the water leaving said coil and before it strikes said articles whenever water is flowing in said coil at the same time, and means 5 for controlling separately the flow of water through said coil and the discharge of said steam, whereby the temperature of the water may be raised to the desired extent and the steam continued after the water flow is discontinued. 10
4. In an article washing machine, means for supporting the articles to be washed and moving them through a prescribed path, means for subjecting the articles to the action 15 of a hot liquid while in said path, a coil immersed in a part of said hot liquid for heat interchange therewith, a continuous pressure water supply connection to one end of said coil, a nozzle device connected to the other end of the coil for discharging water from said coil as a jet against the articles while in said path, a steam connection to said nozzle device, said nozzle device discharging said steam approximately concentrically with the 20 water jet and separately from the jet as it leaves the device but in a manner to cause a thorough mixture of the steam and water immediately after the steam and water leave said device, and means for controlling separately the flow of water through said coil and the flow of steam through said device, whereby the temperature of the water may be raised to the desired extent and the steam continued after the water flow is discontinued. 25
5. In an article washing machine, means for supporting the articles to be washed and moving them through a prescribed path, means for subjecting the articles to the action 30 of a hot liquid while in said path, a coil immersed in a part of said hot liquid for heat interchange therewith, a water supply connection to one end of said coil, a discharge device connected to the other end of the coil 35 for discharging pressure water from said coil against the articles while in said path, means for discharging steam against said articles in a manner to cause its mixture with the water leaving said coil and before it strikes said articles whenever water is flowing in said coil at the same time, and means 40 for selectively controlling the flow of water through said coil and the discharge of said steam independently of one another, whereby 45 the articles may be subjected to a discharge of water, or steam, or a mixture of both, or a succession of any thereof. 50
6. In an article washing machine, an article support, a nozzle device having a passage 55 for discharging a liquid jet therethrough against said articles, means for supplying hot liquid to said passage, said device also having a passage for discharging a jet of steam against said article and in a direction such 60 that the two jets will meet and mix after 65 leaving said device, before striking said article, a steam supply connection to the steam passage of said device, and means for controlling the discharge of steam and water through said device. 70
7. In an article washing machine, means for supporting the articles to be washed and a nozzle device having a passage for discharging liquid therefrom in a direction toward said articles and also having a surrounding circular converging passage for discharging a circular converging jet of steam also towards said articles and in a manner to engage and mix with the discharged liquid before steam and liquid can reach said articles, said device also having steam and liquid supply connections to said circular passage and said first passage respectively. 75
8. In an article washing machine, means for supporting the articles to be washed, a nozzle device having a passage for directing a fluid jet towards said articles and also having a frusto-conical passage converging towards the outer end of said first passage but spaced somewhat therefrom to discharge a separate jet, whereby fluids ejected from said passages will meet and mix after discharge and before striking said articles, means for supplying separate fluids to said passages, and means for controlling the fluid flow through said passages. 80
9. In an article washing machine, a casing, means within said casing for conducting the articles to be washed therethrough in a prescribed path and spaced above the bottom thereof, means for washing said articles at one point in their travel, means for subjecting said articles to a hot liquid rinse at another and subsequently occupied point in said path, a reservoir into which said hot rinse liquid is collected after use, a coil immersed in the rinse liquid in said reservoir for heat interchange therewith, a clean water supply connection to one end of said coil, and means connected to the other end of said coil for directing the hot water therefrom against the articles while in a still further subsequently occupied position in said path. 90
10. In an article washing machine, a casing, means within said casing for conducting the articles to be washed therethrough in a prescribed path and spaced above the bottom thereof, means for washing said articles at one point in their travel, means for subjecting said articles to a hot liquid rinse at another and subsequently occupied point in said path, a reservoir into which said hot rinse liquid is collected after use, a coil immersed in the rinse liquid in said reservoir for heat interchange therewith, a continuous pressure source of clean water connected to one end of said coil, means connected to the other end of said coil for directing a jet of liquid from said coil against the articles to be washed, and means for mixing with said 100
11. In an article washing machine, a casing, means within said casing for conducting the articles to be washed therethrough in a prescribed path and spaced above the bottom thereof, means for washing said articles at one point in their travel, means for subjecting said articles to a hot liquid rinse at another and subsequently occupied point in said path, a reservoir into which said hot rinse liquid is collected after use, a coil immersed in the rinse liquid in said reservoir for heat interchange therewith, a continuous pressure source of clean water connected to one end of said coil, means connected to the other end of said coil for directing a jet of liquid from said coil against the articles to be washed, and means for mixing with said 105
12. In an article washing machine, a casing, means within said casing for conducting the articles to be washed therethrough in a prescribed path and spaced above the bottom thereof, means for washing said articles at one point in their travel, means for subjecting said articles to a hot liquid rinse at another and subsequently occupied point in said path, a reservoir into which said hot rinse liquid is collected after use, a coil immersed in the rinse liquid in said reservoir for heat interchange therewith, a continuous pressure source of clean water connected to one end of said coil, means connected to the other end of said coil for directing a jet of liquid from said coil against the articles to be washed, and means for mixing with said 110
13. In an article washing machine, a casing, means within said casing for conducting the articles to be washed therethrough in a prescribed path and spaced above the bottom thereof, means for washing said articles at one point in their travel, means for subjecting said articles to a hot liquid rinse at another and subsequently occupied point in said path, a reservoir into which said hot rinse liquid is collected after use, a coil immersed in the rinse liquid in said reservoir for heat interchange therewith, a continuous pressure source of clean water connected to one end of said coil, means connected to the other end of said coil for directing a jet of liquid from said coil against the articles to be washed, and means for mixing with said 115
14. In an article washing machine, a casing, means within said casing for conducting the articles to be washed therethrough in a prescribed path and spaced above the bottom thereof, means for washing said articles at one point in their travel, means for subjecting said articles to a hot liquid rinse at another and subsequently occupied point in said path, a reservoir into which said hot rinse liquid is collected after use, a coil immersed in the rinse liquid in said reservoir for heat interchange therewith, a continuous pressure source of clean water connected to one end of said coil, means connected to the other end of said coil for directing a jet of liquid from said coil against the articles to be washed, and means for mixing with said 120
15. In an article washing machine, a casing, means within said casing for conducting the articles to be washed therethrough in a prescribed path and spaced above the bottom thereof, means for washing said articles at one point in their travel, means for subjecting said articles to a hot liquid rinse at another and subsequently occupied point in said path, a reservoir into which said hot rinse liquid is collected after use, a coil immersed in the rinse liquid in said reservoir for heat interchange therewith, a continuous pressure source of clean water connected to one end of said coil, means connected to the other end of said coil for directing a jet of liquid from said coil against the articles to be washed, and means for mixing with said 125
16. In an article washing machine, a casing, means within said casing for conducting the articles to be washed therethrough in a prescribed path and spaced above the bottom thereof, means for washing said articles at one point in their travel, means for subjecting said articles to a hot liquid rinse at another and subsequently occupied point in said path, a reservoir into which said hot rinse liquid is collected after use, a coil immersed in the rinse liquid in said reservoir for heat interchange therewith, a continuous pressure source of clean water connected to one end of said coil, means connected to the other end of said coil for directing a jet of liquid from said coil against the articles to be washed, and means for mixing with said 130

liquid from said coil before it reaches said article a quantity of steam to further heat the liquid from said coil and provide a sterile rinse for said articles.

- 5 11. In an article washing machine, a casing, means within said casing for conducting the articles to be washed therethrough in a prescribed path and spaced above the bottom thereof, means for washing said articles at one point in their travel, means for subjecting said articles to a hot liquid rinse at another and subsequently occupied point in said path, a reservoir into which said hot rinse liquid is collected after use, a coil 10 immersed in the rinse liquid in said reservoir for heat interchange therewith, a clean water supply pressure connection to one end of said coil, means connected to the other end of said coil for directing a jet of liquid from said coil against the articles to be washed and means for mixing with said liquid from said coil before it reaches said article a quantity of steam to further heat the liquid from said coil and provide a sterile 15 rinse for said articles, said casing having means to collect the sterile rinse liquid from said articles and return it to said reservoir to provide a continually renewing hot rinse liquid.
- 20 12. In an article washing machine, a casing, means within said casing for supporting the articles to be washed and conveying them in a prescribed path through said casing and in a position to drain, means within said casing for subjecting said articles first to a 25 cleansing solution and then at a subsequently reached point to a hot liquid rinse, said casing having a tank portion beneath said articles into which said cleansing solution and hot rinse drain separately, a coil immersed 30 in the hot rinse tank, a water connection for continuous clean water attached to one end of said coil, a nozzle connected to the other end of said coil and discharging water from said coil in a direction to strike said articles 35 after the latter have travelled further in the said path, and a steam supply connection associated with said nozzle for adding steam to the liquid leaving said nozzle to further heat 40 the same.
- 45 13. In an article washing machine, a casing, means within said casing for supporting the articles to be washed and conveying them in a prescribed path through said casing and in a position to drain, means within said 50 casing for subjecting said articles first to a cleansing solution and then at a subsequently reached point to a hot liquid rinse, said casing having a tank portion beneath said articles into which said cleansing solution and hot rinse drain separately, a coil immersed 55 in the hot rinse tank, a clean water connection to one end of said coil, a nozzle connected to the other end of said coil and discharging water from said coil in a direction to strike said articles 60 after the latter have travelled further in the said path, and a steam supply connection associated with said nozzle for adding steam to the liquid leaving said nozzle to further heat 65 the same.
- 70 14. In an article washing machine, a casing, means for supporting articles to be washed in said casing and moving them in a prescribed path therethrough, a source of power at the top of said casing, an intermittent drive connection between the upper end of said article moving means and said source of power, whereby said articles will be given increments of movement in said path with intervals of rest between such movements, means for subjecting the articles while in successive 75 positions in said path to successive treatments with cleansing and rinsing liquids, means for subjecting said articles while in further successive positions in their travel to a sterile rinse, and means including valves 80 at the tops of said casing and controlled by said source of power in synchronism with said article moving means for controlling the operation of a sterile rinse subjecting means in any desired sequence.

85 15. In an article washing machine, a casing, means for supporting articles to be washed in said casing and moving them in a prescribed path therethrough, a source of power at the top of said casing, an intermittent drive connection between the upper end of said article moving means and said source of power, whereby said articles will be given increments of movement in said path with intervals of rest between such movements, means for subjecting the articles while in successive 90 positions in their travel to a sterile rinse, and means including valves at the tops of said casing and controlled by said source of power in synchronism with said article moving means for controlling the operation of a sterile rinse subjecting means in any desired sequence.

95 16. In an article washing machine, a casing, means within the casing for supporting 100 articles after the latter have travelled further in said path, and a steam supply connection associated with said nozzle for adding steam to the liquid leaving said nozzle to further heat 105 the same, and means for causing operation of the first recited means and also synchronously therewith controlling the flow of water through said coil and the addition of steam to the water so discharged whereby said articles 110 may be subjected first to a hot sterile rinse of water and steam and then to a subsequent bath of steam only to complete the sterilization.

115 17. In an article washing machine, a casing, means for supporting articles to be washed in said casing and moving them in a prescribed path therethrough, a source of power at the top of said casing, an intermittent drive connection between the upper end of said article moving means and said source of power, whereby said articles will be given increments of movement in said path with intervals of rest between such movements, means for subjecting the articles while in successive 120 positions in their travel to a sterile rinse, and means including valves at the tops of said casing and controlled by said source of power in synchronism with said article moving means for controlling the operation of a sterile rinse subjecting means in any desired sequence.

125 18. In an article washing machine, a casing, means within the casing for supporting 130 articles while at a further successive position along said path, a jet of hot rinse liquid, means for adding steam to the discharged rinse liquid, and valve means for said steam and rinse liquid at the top of said casing and operated in synchronism with the intermittent movement of said articles by said source of power for first directing a mixture of steam and rinse liquid towards said articles and then prolonging the steam discharged against said articles for an interval after the cessation of flow of rinse liquid.

- and moving in a prescribed path, the articles to be washed, a source of power including a shaft extending across the top of said casing, an intermittent drive connection between said shaft and said means, whereby said articles will be given intermittent increments of movement with intervals of rest between such movements during continuous rotation of said shaft, valve means at the top of said 5 casing, and cams operated by said shaft in synchronized relation to said intermittent drive for subjecting said articles to treatments of water and steam and then steam at one point in the travel of the articles.
- 10 17. In an article washing machine, a casing, means within said casing for supporting and moving therethrough articles to be washed, a source of power including a continuously rotating shaft extending across the 15 top of said casing, a Geneva transfer and locking connection between said shaft and said means, whereby said means will be given intermittent increments of movement with intervening intervals of rest, and said means 20 will be locked against movement while in said intervals of rest, and means including valves and controlling cams therefor operated by said shaft in synchronized relation to said Geneva transfer mechanism for determining 25 successive treatments to which said articles 30 may be subjected while moving through said casing.
18. In an article washing machine of the rotary conveyor type, a casing, a vertical 35 shaft in said casing, means mounted on said shaft and supporting the articles to be washed and conveying them in an arcuate path through the casing during rotation of the shaft, a Geneva gear connected to one end 40 of said vertical shaft for driving the same, a power shaft at the same end of the machine, means operated by said power shaft and operating said Geneva gear step by step to cause step by step travel of said articles, means in 45 said casing for subjecting the articles while in different positions of rest in said travel to the action of jets of water and steam, valves controlling said water and steam separately, and means operated by said power 50 shaft for in turn operating said valves in a desired sequence to direct a mixture of steam and water against said articles and then to continue the steam after the water is shut off.
- 55 19. In an article washing machine of the rotary type, a casing, a vertical shaft in said casing, a support carried by said shaft and mounting the articles to be washed and conveying them in an arcuate path through said 60 casing, a Geneva gear mounted on said shaft, a power shaft at the end of the shaft adjacent said gear, gearing between said shaft and Geneva gear for operating the latter in a step by step manner during continued rotation of said power shaft, a plurality of valves,
- means operated by said power shaft for operating said valves in a prescribed sequence and for prescribed durations, and means controlled by said valves for subjecting the articles to the action of fluid jets in desired sequence while being carried through said casing. 70
